UNITED STATES PATENT OFFICE.

DENNIS PARKS, OF ST. LOUIS, MISSOURI.

ADJUSTABLE CLAMP FOR LOG-HOLDERS.

1,385,188.

Specification of Letters Patent. Patented July 19, 1921.

Application filed June 18, 1920. Serial No. 390,017.

To all whom it may concern:

Be it known that I, DENNIS PARKS, a citizen of the United States, residing in the city of St. Louis and State of Missouri, have invented new and useful Improvements in Adjustable Clamps for Log-Holders, of which the following is a specification.

This invention relates to heel log holders and has for its general object to provide an adjustable clamping mechanism whereby the pressure on the log may be simultaneously and uniformly adjusted throughout its length.

In the manufacture of heels from pieced lifts, it is customary to build a log of pieced lifts which is gradually forced downward in a log holder, which may be of very considerable length, extending through one or more floors of the building. It is desirable to produce sufficient frictional resistance to the movement of the log in the holder to create the necessary pressure to cause the pasted sections of the log to be firmly compressed together by the act of forcing the log through the holder as it is built up by the addition of pieces of leather applied at the top of the log. Heretofore, where the log holder has been of considerable length, it has been necessary for the operator to make several adjustments at different heights on the log holder, and it has been found very difficult to make such adjustments uniform; and at the best, the present means of adjustment requires the operator to go to different floors of the building to make the adjustments, which, of course, consumes considerable time.

According to my invention the clamping plate, or plates, on the log holder can be adjusted throughout the entire length of the holder at one point and by a single manipulation.

The invention is illustrated in the accompanying drawing in which:

Figure 1 is a view in broken side elevation showing a portion of the heel builder with a log holder thereon having my invention applied thereto.

Fig. 2 is a view in front elevation of a portion of a log holder with my invention applied thereto, and

Fig. 3 is a sectional plan view on the line 3—3 of Fig. 1.

Referring now to the drawing, the numeral 1 indicates generally the frame of the

heel building machine in which operates a plunger 2 for pressing the heel lifts downward in the log holder 3. The numeral 4 indicates an inclined platform on which the heel lifts or heel blanks are assembled, the numeral 5 a gage against which heel blanks may be built up and the numeral 6 a suitable carriage for moving the built up heel blanks off of the table 4 and into the holder 3 in position to be operated on by the plunger 2.

The particular construction of which a portion is shown in this drawing is the same as illustrated in my pending application Ser. No. 344,287, filed December 12, 1919. It is also shown in my pending application Ser. No. 344,288, filed December 12, 1919. In the present case as in the case of the two applications referred to, it is contemplated that heel blanks shall be built up on the table 4 and forced in order into the log holder where they are held under compression by frictional engagement with the walls of the holder. However, it will be clearly apparent from the description to follow that my invention is equally applicable, and in fact, is equally intended to apply, to the use of a log holder for logs built up of pieced lifts, as above set forth in the statement of invention.

My invention is shown embodied in connection with a device intended for building up heel blanks, not only to illustrate such application of the invention but because the assembling of heel blanks in a holder, as distinguished from the building up of a continuous log, is a method now widely used, and particularly in connection with prior machines and inventions of mine, and others jointly interested with me in such inventions.

The holder 3 comprises generally a front or breast plate 7 which is rigid, and against which the breast of the heel blank 8, or of the heel log is adapted to rest and a back plate 9 which is recessed to receive the major portion of the rounded part of the heel, or heel log, as clearly shown in said Fig. 3. Both of the plates 7 and 9 may be of indefinite length and, as stated, the breast plate 7 is rigid, being secured at its upper end to the frame 1 as indicated at 10 and throughout its length to suitable supports, not shown, in a well known manner. At suitable intervals throughout the length of the log holder the plates 7 and 9, constitut-

ing the log holder, are encircled by yokes 11 which are slidably mounted on guides 12 provided on either side of the front plate 7. The rear inner side of each yoke 11 engages 5 the inner side of the back plate 9 as shown by Fig. 3 and in the front side of each yoke there is mounted an adjusting bolt 13 which passes through the yoke and engages the front side of the breast plate 7. On the upper 10 adjusting bolt 13 there is mounted a sprocket wheel 14 and on the lowermost adjusting bolt a similar sprocket wheel 15, over which sprocket wheels is passed a chain 16. At intermediate points in the length of 15 the log holder the adjusting bolts 13 are provided with sprocket wheels 17, one of which is shown in Fig. 2, each of said sprocket wheels being engaged on either side by the sprocket chain 16. A guard 18 20 is mounted on the yoke 11 of each of the sprocket wheels 17 which embraces the sprocket chain 16 on either side of each sprocket wheel 17 in order to maintain sprocket chain 16 in engagement with the 25 teeth of said sprocket wheel 17. It will readily be seen that by turning the adjusting bolts 13 they will be caused to bear against the rigid breast plate 7 and to move the yokes 11 outward, thereby drawing the 30 back plate 9 toward the breast plates 7 to produce the requisite degree of pressure upon the heel blanks 8, or the log, as the case may be in the holder 3.

It will also be readily seen that the operator 35 by grasping the chain 16 and turning it at any point in the length of the log holder, will correspondingly turn all of the adjusting bolts 13 so that the back plate 9 will be uniformly moved toward the breast 40 plate 7 throughout the length of the holder. As this adjustment can be made at any point in the length of the holder, where the operator may be stationed, it is evident that he can at all times accurately determine the 45 pressure on the heel log, or the column of compiled heel blanks throughout the length of the log holder without the necessity of leaving his position.

I claim:

50 1. A log-holder having an open upper end for receiving heel-blanks, lifts or the like to form the log and extending thence downward for an indefinite distance, said holder comprising two members providing between them an uninterrupted space throughout the length of the holder for accommodating the log, one of said members being movable for varying the area of said space, and means for adjusting said movable member uniformly throughout its length relative to the other member from any point in the length of the holder.

55 2. In combination with a log holder comprising two opposed members of indefinite length providing between them an uninterrupted

space throughout the length of the holder for accommodating the log, one of said members being movable for varying the area of said space, a plurality of means located at different points throughout the 70 length of the log holder and bearing on the outer face of said movable member for adjusting the same relative to the other member, and means for simultaneously and uniformly operating said adjusting means. 75

3. A log-holder having an open upper end for receiving heel-blanks, lifts or the like for forming the log and extending thence downward an indefinite distance, 80 said holder comprising two opposed members providing between them an uninterrupted space throughout the length of the holder for accommodating the log, one of said members being adjustable for varying the area of said space, a plurality of means 85 stationed at points remote from each other throughout the length of the log-holder for adjusting said member, and means for simultaneously operating all of said means from any point in the length of the holder. 90

4. A log-holder having an open upper end for receiving heel-blanks, lifts or the like for forming the log and adapted to extend thence downward an indefinite distance, through separated zones of accessibility to the holder, said holder comprising two opposed members providing between them an uninterrupted space throughout the length of the holder for accommodating the log, one of said members being movable for 100 adjusting the area of said space, a plurality of adjusting devices located at points remote from each other throughout the length of the log-holder for adjusting said movable member toward and from the other member 105 and means common to all of said devices for simultaneously and uniformly operating them from any point in the length of the log-holder.

5. In combination with a log holder comprising two members providing between them an uninterrupted space throughout the length of the holder for accommodating the log, one of said members being movable for clamping the log, a series of devices for 110 moving said clamping member comprising adjusting bolts operating wholly on the exterior of said clamping member, and means operatively connecting all of said adjusting bolts and operable from any point in the 115 length of the holder to simultaneously turn all of said bolts whereby to uniformly adjust said clamping member throughout the 120 length of the holder.

6. In combination with a log holder comprising two members providing between them an uninterrupted space throughout the length of the holder for accommodating the log and having a clamping member, a plurality of devices for moving said clamping 125 130

member comprising adjusting bolts provided with sprocket wheels and located at different points throughout the length of the holder, said bolts operating wholly on the exterior of said clamping member, and a sprocket chain coöperating with all of said sprocket wheels whereby by turning said

chain all of said bolts may be simultaneously turned to uniformly adjust said clamping member.

10

In testimony whereof, I have hereunto set my hand.

DENNIS PARKS.
